TELEPHONE-CALL TALLY APPARATUS

Ervin G. Johnson, Eureka, Calif.

Application March 16, 1938, Serial No. 196,195

2 Claims. (Cl. 40—10.5)

This invention relates to telephones and more particularly to a telephone call tally.

It is the principal object of this invention to provide a low cost and effective telephone call tally device. Subordinate objects will become manifest from a consideration of the following specification in which reference is made to the drawing for illustration of a preferred embodiment.

In the drawing:

Fig. I is a plan view of a fragment of a telephone with a tally device mounted thereon;

Fig. II is a sectional view taken at the line II—II of Fig. I; and

Fig. III is an enlarged sectional elevation of the pad and its securing means as shown in Fig. I.

A conventional telephone having a dial 4 rotatably mounted so as to rotate about an axis through its center, said dial having a conventional index card holder 6 provided with an inwardly and downwardly directed lip or flange 8, has mounted over the window 10 of said index holder a small pad 12, or 12', preferably rectangular in plan. The dimensions of the pad 12 are such that it fits snugly in the recess 14 formed by flange 8. The longer axis of pad 12 is preferably normally horizontal.

The pad 12 comprises a backing sheet of cardboard 16, and a plurality of sheets 18 and 20, the thickness of the sheets in the drawing being exaggerated for the purpose of better illustration. The sheets 18 and 20 may be of equal length, but both sets of sheets are shorter than the cardboard back 16 by a distance f . The sheets 18 of one set are spaced apart by the thickness of a sheet 20. The converse is true of the sheets 20. The ends of the sheets 18 are all bound down or padded tightly at the end A as indicated at 22 by stitching, stapling, or gluing them to the cardboard back 16. The sheets 20 are similarly bound at the end A' of the pad.

The binding 22 is preferably placed substantially beyond the free ends b of the intervening sheets. Means are also preferably provided to permit easy severance of the sheets from the pad, as for example a row of perforations 24 beyond the ends b of the intervening sheets.

The sheets are successively numbered, the serial numbering being progressive or retrogressive from the top down, as desired.

The sheets may also be provided with numerals representing progressive days of the month stamped thereon, one or more successive sheets having the same date number depending upon

the number of calls, and hence, sheets, assigned to the particular date.

The use of the pads is activated by their distribution as advertising matter. To this end the advertiser's name and telephone number may be inscribed on each of the sheets in the manner shown in Fig. I.

A finishing tape 26 may be provided at each bound end of the pad to render the same neat in appearance.

Referring to Fig. III it will be noted that the manner of binding causes the bound ends of the sheets to be bent down due to the fact that the central portion of the pad is twice the thickness of the bound ends. The bound sheets are therefore placed under a strain and tend to straighten when released, as shown by the position taken by the topmost sheet 20, the free end of which lies well above the remaining sheets 18 and 20 of the pad. This facilitates engagement of this sheet by the hand. Only one sheet can be engaged for it is apparent that the next lower sheet has its free edge (at the right in Fig. III) tucked under the topmost sheet. The edges b of all sheets below the topmost sheet are protected from mutilation by reason of their lying between the adjacent sheets which are bound together thereby.

As soon as the topmost sheet is torn away, the free edge of the next lower sheet becomes free to spring up, and that sheet then becomes the topmost sheet in turn.

A dozen or more of the pads remaining mechanically bonded together for manual separation, provides for their handling prior to reaching the consumer, they being saleable in a quantity adequate for one telephone for a year.

The individual pads are secured in the recess 14 of the dial 4 by any suitable means, as for example by a strip of relatively stiff though manipulatively bendable spring metal 34 of sufficient length to permit both of its ends engaging under the flanges 8. Each end of the strip may be arcuate as indicated at 36 and a perceptible lip 38 may be provided so that it will engage within the flange as shown.

The metal strip 34 is passed between the backing 16 and the bottommost sheet of the pad in the manner indicated in Fig. II.

Having described my invention and explained its purpose it will be understood that various modifications thereof may be resorted to without departing from its spirit. Reference is to be had to the following claims for what I claim as my invention.

I claim:

1. In combination, a telephone having a rotatable dial provided with a card holder carried thereby and rotatable therewith; a pad comprising a number of sheets of individually removable character, a backing for said pad, the sheets being of a size only sufficient to permit manual engagement to tear the sheets from the pad, and means engaging the cardholder and between the backing and the pad sheets to hold the pad on the dial with the removable sheets disposed away from the card holder and toward the dial user, alternate sheets of the pad having a single edge fastened to the backing at opposite ends of the backing.

2. In combination, a telephone having a dial provided with a cardholder carried thereby; a pad comprising a number of sheets of individually removable character, a backing for said pad, the sheets being of a size only sufficient to permit manual engagement to tear the sheets from the pad, and means engaging the cardholder and between the backing and the pad sheets to hold the pad on the dial with the removable sheets disposed away from the cardholder and toward the dial user, alternate sheets of the pad having a single edge fastened to the backing at opposite ends of the backing.
